UNITED STATES PATENT OFFICE

JOHN F. GAIL, OF EVANSTON, ILLINOIS

COMBINED INKWELL AND PEN SUPPORT

Application filed November 22, 1928. Serial No. 321,116.

This invention relates to combined inkwells and pen supports and has for its principal object to provide a device for normally supporting a pen in upright position with the pen-point immersed in a supply of ink, the depth of immersion being limited. Other objects are to provide a device of the above-described character in which evaporation of the ink from the ink supply is substantially prevented when the pen is supported by the device; to provide means whereby the quantity of ink into which the pen is dipped may be maintained substantially constant with great facility, and to provide a combined inkwell and pen support which may be easily and quickly cleaned.

Other objects and advantages will be understood by reference to the following specification and accompanying drawings, in which I have illustrated two selected forms of combined inkwell and pen support, each of which embodies the features of my invention.

In the drawings:

- 25. Fig. 1 is a plan of one form of my invention.
- Fig. 2 is a section on the line 2—2 of Fig. 1.
- Fig. 3 is a section on the line 3—3 of Fig. 2.
- Fig. 4 is a plan of a second form.

Referring now to the drawings, with particular reference to Figures 1 to 3 inclusive, one form of my invention includes a main reservoir 6 which is adapted to receive a supply of ink, indicated at 8, and a cover 9 provided for closing the top of the reservoir 6. The cover 9 is preferably secured to the main reservoir 6 by means of interengaging screw threading 10 on the inside of the depending annular top flange 25 and on the outside of the upper marginal side portion of the reservoir.

The cover is provided with an upwardly extending annulus 11 which is apertured as at 12 to provide an opening through which the pen-point 13 of a pen may be passed. The

aperture 12 is preferably of such a size that the pen-point may pass freely therethrough without engaging the sides of the aperture, and the diameter of the annulus immediately above the opening 12 is such that the lower 50 end 14 of the penholder 15 will fit freely therein and rest upon the shoulder 16 which is formed as an incident to the above-described construction. It will be seen that, provided the penholder 15 is maintained in 55 a position coaxial with the aperture 12, the end of the pen will serve to close the opening 12 so that evaporation of ink is prevented when the penholder is in place, as shown in Figure 2.

For maintaining the pen in such coaxial position, I provide the annulus 11 with an inner lining of absorbent material 17, which reduces the inside diameter of the annulus so that the penholder 15 is engaged at a point 60 spaced upwardly from the shoulder 16 and thereby maintained substantially in said coaxial position. The absorbent filler 17 may be of any suitable absorbent material, for instance, blotting paper, and may be made up in the form of rings or washers and piled, one over the other, until the recess 18 is properly filled. The inside surface of the absorbent material is preferably lined with a fine mesh screen 19, which may be of metal or other material and which will serve to prevent cutting or picking out of the absorbent material by engagement therewith of the pen-point 13. A cap member 20 threadedly engaging the upper end of the annulus 11, as shown in Figure 2, may be provided for preventing outward endwise displacement of the absorbent packing 17 and also to finish off the top of the annulus 11. Preferably, the pen-receiving space inside of the annulus is made bell-shaped or outwardly flaring, as shown, to facilitate insertion of the pen into the holder.

In devices of this character, it is preferable that the pen-point be immersed in the ink supply to a predetermined limited depth, and 90

not in excess thereof, so that when the pen is withdrawn for writing, it will carry sufficient ink to write freely, but not such a large supply that there would be a serious danger of blotting the work due to ink dropping from the pen point. For this reason, I provide an auxiliary receptacle 21, preferably of rectangular shape and provided on its opposite sides with pairs of ears or lugs 22-22 which extend laterally outwardly from the said sides. The lugs 22 of the auxiliary receptacle 21 are adapted to engage lugs or hangers 23-23 which are preferably formed integrally with the cover 9. The arrangement for mounting the auxiliary receptacle 21 is preferably such (as shown in Figure 2) that the receptacle cannot be unseated from the hangers 23 when the cover is in place on the main reservoir 6, but may readily be removed when the cover is removed from the said reservoir. By inspection of Figure 2, it will be seen that the rectangular receptacle 21 is slidable longitudinally on the hangers 23-23 and that the receptacle cannot be moved endwise sufficiently to disengage the lugs 22-22 and hangers 23-23 because of the limited space 24 between the wall of the reservoir 6 and the adjacent end of the receptacle 21. However, when the cover 9 is removed from the receptacle, the space between said end of the receptacle and the inner wall of the depending cover flange part 25 is sufficient to permit such disengagement of the lugs and hangers so that the receptacle may be removed or separated from the cover for cleaning or other purposes.

When the parts are assembled as shown in Figure 2, the pen-point 13 projects into the receptacle to a limited depth, so that when the receptacle is filled with a supply of ink the pen-point will accordingly be immersed only to a predetermined limited depth. For facilitating the maintenance of a full supply of ink in the auxiliary receptacle 21, I provide a pump mechanism which draws a quantity of ink from the supply 8 in the main reservoir 6 and delivers such quantity to the auxiliary receptacle 21.

The above-mentioned pump mechanism in the present instance includes a depending post-like part 26 which is preferably formed integral with the cover 9 and which is provided with a well 27 which communicates with the supply 8 of ink in the main reservoir through an aperture or port 28 in the lower end of the part 26. A soft rubber bulb 29, which tends to retain its expanded position as shown in Figure 2, is provided for drawing a quantity of ink from the supply 8 into the well 27 through the said port 28. A ball member 30 is disposed in the lower end of the well 27 and normally serves to close the port 28 so that the quantity of ink in the well 27 cannot pass outwardly through the port 28 when the bulb 29 is collapsed. A

passageway 31 is provided in the post member 26 for conveying a quantity of ink in the well 27 to the receptacle 21, and this passageway 31 communicates with the lower end of the well 27 through the agency of a ball check valve member 32. It will be readily understood that when the bulb 29 is collapsed, the quantity of ink in the lower end of the well 27 will be forced through the openings of the check valve 32 and through the passageway 31 into the auxiliary receptacle 21. The check valve 32 serves to prevent the return of ink or air from the passageway 31 into the well 27 when the bulb 29 expands so that a new quantity of ink is drawn into the well 27 from the main reservoir 6 through the port 28. Pins such as shown at 33 and 34 may be provided for maintaining the ball valve members in operative position relative to the respective valve seats.

The second form of my invention, shown in Figures 4 and 5 of the drawings, is a somewhat simplified form and accordingly involves certain advantages over the above described embodiment. The second form may comprise a main reservoir 40 which receives and holds a supply of ink 41. A cover 42 for the main reservoir is provided and may be secured to the latter by means of screw-threadedly interlocking portions, as clearly shown in Figure 5. The cover 42 in this embodiment is provided with an upwardly projecting annulus 43 having an aperture 44 in its lower end for permitting the passage of a pen-point therethrough as clearly shown. The annulus 43 is preferably formed with an outwardly flaring internal chamber so as to facilitate insertion of the pen thereto, and a shoulder 45 is formed to support the pen by engaging the lower end of the pen holder as clearly shown.

The cover 42 is provided with a central aperture 46 and a depending annular flange 47 which in effect lengthens said aperture, and an auxiliary receptacle 48 having an upwardly projecting post member 49 is removably mounted in the said aperture 46 by sliding the post part 49 through said aperture. In Figures 4 and 5, I have shown the main reservoir as being substantially circular in plan. In this case, the auxiliary receptacle 48 is also substantially circular in plan and fits inside of the reservoir 40 quite closely, leaving only a comparatively narrow space, indicated at 50, between the outside of the auxiliary receptacle and the inside of the reservoir. The post 49 is preferably hollowed out, and a compressible spring 51, positioned inside of the hollow post 49 and between the upper end of the same and the bottom of the reservoir, serves to normally maintain the reservoir in its uppermost position, as shown in Figure 5, the receptacle being limited in upward movement by the engagement shown at 52 between the lower

end of the flange 47 and an annular boss provided in the bottom of the auxiliary receptacle around the post 49.

A supply 41 of ink being in the main reservoir 40, the auxiliary receptacle 48 may quickly and easily be filled by merely depressing the same against the pressure of the spring 51 by pressing on the top of the post 49. The receptacle 48 when so depressed displaces the supply of ink 41 which passes upwardly through the space 50 between the outside of the receptacle 48 and inside of the reservoir 40 and flows into the receptacle 48. When the receptacle is filled, the post 49 may be released and the spring 51 will raise the receptacle to its normal up position.

It will be understood that in both of the above-described forms of my invention, ink may initially be supplied to the main reservoir by pouring through the pen support or annulus, or that the cover may be removed from the main reservoir to afford access to the same. In both forms of my invention, the auxiliary reservoir is removably mounted with respect to the cover and may be readily separated therefrom for cleaning or other purposes. Obviously, in both forms of my invention, the pen-point is immersed in ink to a maximum and substantially uniform depth, independent of wide variations in the depth of ink in the main reservoir.

It is not, of course, necessary that the auxiliary receptacle be maintained entirely full at all times, since the pen-point would receive sufficient ink to write even though the auxiliary receptacle were not completely filled. However, because of the great facility with which the auxiliary receptacles may be maintained full, it is probable that in actual use they would be maintained substantially full at all times so as to obtain the greatest writing efficiency from the pen.

If a fountain pen of the self-filler type is used, the pen reservoir may be replenished quickly and conveniently from time to time without danger of inserting the point end of the penholder far enough into the ink receptacle to wet the lower end of the barrel.

I am aware that changes may be made in the form, construction and arrangement of parts without departing from the spirit of my invention, the scope of which should be determined by reference to the following claims, construing the same as broadly as possible consistent with the state of the art.

I claim as my invention:

1. In an inkstand of the class described, the combination of a main reservoir, an auxiliary ink receptacle within said reservoir and arranged to overflow thereinto, means for supplying ink from said reservoir to said receptacle, and means for normally supporting a pen in upright position with the pen-point immersed in said auxiliary receptacle, said means comprising a part having an opening

permitting only the pen-point to pass therethrough and into said auxiliary receptacle, said opening being of such size that the surrounding portion thereof engages a part of the penholder to prevent the same from passing through said opening and into said ink, said part being thereby effective to normally support said pen with its pen point submerged in the ink in said auxiliary receptacle to a predetermined limited depth.

2. In an inkstand of the class described, the combination of a main reservoir, an auxiliary ink receptacle within said reservoir and arranged to overflow thereinto, means for supplying ink from said reservoir to said receptacle, and means for normally supporting a pen in upright position with the pen-point immersed in said auxiliary receptacle, said means comprising a tubular member having an opening adjacent its lower end permitting the pen-point only to pass therethrough and into said auxiliary receptacle, said opening being of such size that the surrounding portion of said tubular member engages a part of the penholder to prevent the same from passing through said opening, whereby said member serves to limit the depth of immersion of said pen-point, a portion of said tubular member spaced upwardly from said opening also engaging said pen holder for maintaining the same substantially coaxial with said opening, whereby said pen holder serves to close said opening so as to prevent excessive evaporation of the ink in the inkstand.

3. In an inkstand of the class described, the combination of a main reservoir having an open top, a removable cover for said open top, an auxiliary receptacle removably mounted on said cover and disposed within said main reservoir when said cover is in place thereon, said auxiliary receptacle being arranged to overflow into said reservoir, means for supplying ink from said main reservoir to said auxiliary receptacle, and means carried by said cover for supporting a pen in upright position with the pen-point only immersed in said auxiliary receptacle to a predetermined, limited depth when the latter is full, said pen-supporting means being constricted so as to permit only the passage of the pen-point therethrough and into said auxiliary receptacle.

4. In an inkstand of the class described, the combination of a main reservoir, an auxiliary receptacle within the upper portion of said reservoir and arranged to overflow thereinto, means for supplying ink from said reservoir to said receptacle, a single cover for said reservoir and said receptacle and serving to support the latter, and means for normally supporting a pen in inclined upwardly extending position with the pen point immersed in said auxiliary receptacle, said means comprising an inclined tubular member extending upwardly from said cover,

said cover being provided with an opening therein adjacent the lower end of said tubular member and coaxial therewith, said opening being of such a size as to permit a pen point to pass therethrough and into said receptacle while preventing the lower end of the penholder from being inserted into said receptacle, thereby to limit the depth to which the pen point may be inserted in said receptacle, and a lining of absorbent material in said tubular member for absorbing ink inadvertently deposited thereon, thereby to prevent ink from accumulating on the inside wall surface of said tubular member whereby the pen holder is kept clean.

5. In combination with an ink receptacle having an opening in the upper portion thereof, pen supporting means comprising a tubular member in axial alignment with said opening and communicating therewith, said tubular member being of such diameter as to permit a pen point to pass therethrough and into said receptacle while preventing the lower end of the pen holder from being inserted into said receptacle, whereby to limit the depth to which the pen point may be inserted in said receptacle, a lining of absorbent material in said tubular member for absorbing ink inadvertently deposited thereon, and protective means covering said absorbent lining to prevent the pen point from penetrating said lining.

6. A pen support comprising a tubular member, a lining of absorbent material in said tubular member, and a foraminous protective covering over said absorbent lining.

7. In an inkstand of the class described, the combination of a main reservoir, an auxiliary ink receptacle within said reservoir and arranged to overflow thereinto, means for supplying ink from said reservoir to said receptacle, a single closure member for said reservoir and said receptacle, and means arranged on said closure member for normally supporting a pen in upright position and having a constriction therein whereby a penholder will be prevented from entering said receptacle and the pen-point carried by said holder may be immersed to a predetermined maximum depth in the ink carried by said receptacle.

8. A device as described in claim 7, wherein in said ink-supplying means consists of a pump and said pump and receptacle are both carried by said closure member.

9. In a device as defined in claim 7, resilient means supporting said receptacle in elevated position, and means carried by said receptacle and extending through said closure member where it may be readily grasped for depressing said receptacle against the action of said resilient means to the lower portion of said reservoir for filling said receptacle with ink automatically, said closure

member having an opening through which slidably extends said depressing means.

10. In a device as defined in claim 7, resilient means supporting said receptacle in elevated position, and handle means carried by said receptacle and extending through said closure member where it may be readily grasped for depressing said receptacle against the action of said resilient means to the lower portion of said reservoir for filling said receptacle with ink automatically, the outer contour of said receptacle being similar and nearly equal in dimensions to the inner contour of said reservoir whereby substantially the entire contents of said reservoir may be transferred to said receptacle and said closure member having an aperture through which slidably extends said handle means.

11. In an inkstand of the class described, the combination of a main reservoir, an auxiliary ink receptacle disposed within said reservoir and arranged to overflow thereinto, resilient means supporting said receptacle in the upper portion of said reservoir, a single closure member for said reservoir and said receptacle, and handle means carried by said receptacle and extending through said closure member where it may be readily grasped for depressing said receptacle to the lower portion of said reservoir against the action of said resilient means where it may be filled with ink automatically, said closure having an aperture therein for the insertion of a pen and an aperture of such size as to permit the sliding passage of said handle means.

12. In an inkstand of the class described, the combination of a main reservoir, an auxiliary ink receptacle within said reservoir and arranged to overflow thereinto, a single closure member for said reservoir and said receptacle, a tubular member carried by said receptacle and extending through said closure member, said tubular member serving as a handle for depressing said receptacle to the lower portion of said reservoir where it may be filled with ink automatically, and a helical spring disposed within said tubular member and supported on the bottom of said reservoir for resiliently maintaining said receptacle in elevated position, said closure member having an aperture therein for permitting the immersion of a pen in said receptacle and an aperture of such size as to permit sliding passage of said handle.

13. In an inkstand of the class described, the combination of a main reservoir, an auxiliary ink receptacle within said reservoir and arranged to overflow thereinto, a single closure member for said reservoir and said receptacle, a tubular member carried by said receptacle and extending through said closure member, said closure member having an opening through which slidably extends

5 said tubular member, said tubular member serving as a handle for depressing said receptacle to the lower portion of said reservoir where it may be filled with ink automatically, a helical spring disposed within said tubular member and supported on the bottom of said reservoir for resiliently maintaining said receptacle in elevated position, and means arranged on said closure member 10 for normally supporting a pen in upright position and having a constriction therein whereby a penholder will be prevented from entering said receptacle and the pen-point carried by said holder may be immersed to a predetermined maximum depth in the ink carried by said receptacle.
